(57) **CLAIM**

We claim the ornamental design for an air moving apparatus, as shown and described.

DESCRIPTION

FIG. 1 is a front perspective view of an air moving apparatus embodying the present invention;

FIG. 2 is a front view of the air moving apparatus of FIG. 1; FIG. 3 is a rear view of the air moving apparatus of FIG. 1; FIG. 4 is a right side view of the air moving apparatus of FIG. 1;

FIG. 5 is a left side view of the air moving apparatus of FIG. 1;

FIG. 6 is a top view of the air moving apparatus of FIG. 1; and, FIG. 7 is a bottom view of the air moving apparatus of FIG. 1, the unclaimed environmental stand for the air moving apparatus which is shown in broken lines in FIGS. 1-6 is not shown in this FIG. 7 for purposes of clarity.

The broken lines shown herein are for illustrative purposes only and form no part of the claimed design.

1 Claim, 7 Drawing Sheets
